CONTROL PANEL FOR A COMBINED RADIO AND PHONOGRAPH OR SIMILAR ARTICLE

Herbert J. Zeller, Dundee, Ill., assignor to Motorola, Inc.,
Franklin Park, Ill., a corporation of Illinois

Original design application Nov. 1, 1965, Ser. No. 87,970,
now Patent No. 210,100, dated Feb. 6, 1968. Divided
and this application Sept. 28, 1967, Ser. No. 9,703

Term of patent 14 years

(Cl. D56—4)

FIG. 1 is a front elevational view of a control panel for a combined radio and phonograph or similar article showing my new design;

FIG. 2 is a right side elevational view, the opposite side being substantially a mirror image thereof; and

FIG. 3 is a top plan view thereof.

The broken line showing of a portion of a combined radio and phonograph in which the control panel may be mounted is for illustrative purposes only.

This application is a divisional application of the application Ser. No. D. 87,970, filed Nov. 1, 1965 and now patent D. 210,100.

I claim:

The ornamental design for a control panel for a combined radio and phonograph or similar article, as shown and described.
